CORNER MOUNT AND METHOD AND MACHINE FOR MAKING THE SAME

William B. Miner, Reading, Mass., assignor to
Ace Art Company, Reading, Mass., a corpora-
tion of Massachusetts

Application May 16, 1947, Serial No. 748,624

4 Claims. (Cl. 40—158)

1

This invention relates to corner mounts for photographs, cards, or the like, and to a method of and machine for making such mounts.

While not restricted to such material, the mount construction in accordance with this invention is particularly suitable where the outer portion or cap which overlies the photograph or card when in use is made of transparent material such as cellophane, or the like. This mount comprises a pair of elements glued or otherwise cemented together, the outer or cap element comprising a layer having angularly related margins folded under and secured to the outer face of the second or base element. When a transparent mount is desired, the outer folded-in cap is made of transparent material, while the other or base element may comprise a flat piece of paper. In the making of such a mount, the cap element is formed by folding inwardly the end corners of a strip of cap material and then applying a punching from a strip of the base material, the punching having an activated adhesive for contact with the folded-in corners of the cap element.

In order to provide for proper feed, the machine provides for leaving the folded cap element partly attached to a cap strip while the folding of the cap for the succeeding mount is accomplished, the subsequent action of the machine in presenting and attaching the base element acting to completely sever the mount from the cap blank after which the cap blank with the folded succeeding cap element is presented to the position where the base element is attached and a successive portion of the cap blank is folded.

For a complete understanding of this invention, reference may be had to the accompanying drawings in which

Figure 1 is a horizontal cross sectional view of a machine for making the mounts, the section being taken between the strip feeding and manipulating mechanism and the punch mechanism which latter is then in elevated position.

Figure 2 is a front elevation of the same and showing the lower end of the punch which stamps the base element of the mount from the base strip and applies it to the cap element.

Figure 3 is a right hand end elevation of the same.

Figure 4 is a detail sectional view on line 4—4 of Figure 1.

Figure 5 is a fragmentary top plan view of the cap strip manipulating means in position after it has been cut inwardly in preparation for the forward corners at the cut to be inwardly folded.

Figure 6 is a detail sectional view on line 6—6 of Figure 5, this view also showing the punch by which the base element is cut from the base strip material and presented against the cap.

Figure 7 is a view similar to a portion of Figure 5, but showing the cap strip corners folded.

Figure 8 is a detail sectional view on line 8—8 of Figure 7.

Figure 9 is a view similar to Figures 5 and 7, 10 but showing the folders retracted and the punch in section and applying the punching to the folded cap element and severing it from its strip.

Figure 10 is a detail sectional view on line 10—10 of Figure 9.

Figure 11 is a fragmentary plan view of the folded cap strip showing two units folded and just prior to the severance of the first from the cap strip.

Figure 12 is a fragmentary perspective view of 20 the cap strip supporting die plate.

Figure 13 is a detail sectional view on line 13—13 of Figure 12.

Figure 14 is an exploded perspective view of the cap and base elements of a mount.

Figure 15 is a perspective view of the completed mount.

Referring to the drawings, the machine shown is of the general type illustrated in the Riley Patent No. 1,627,667, the two strips from which the mounts are made being fed in angularly disposed relation, one above the other, the lower one being folded and the upper one being punched when it passes across above the lower end, the punching being applied and cemented to the folded piece. In the case of the present invention, however, where it may be desired to employ a transparent cap, this cap is the folded member and the base element is punched from the base strip and is secured to the folded element.

The cap strip 10 is fed in intermittently, as by 40 the rotation of a feed roll 11 (Figure 1), having a segmental element 12 yieldingly fixed thereto similar to the feed roll shown in Figure 8 of the Riley patent hereinbefore mentioned. This strip may well be formed of very thin cellophane where a transparent mount is desired. It is fed lengthwise along the upper face of a die plate 15 and beneath a cover plate 16 secured to the die plate as by screws 17.

Toward its forward end, as shown best in Figure 12, the die plate 15 is provided with a depression 17' of a width to receive the strip 10 between its upstanding side edges 18. These side edges 18 terminate in a pair of upstanding edge portions 19 arranged at right angles to each

other and which meet centrally in an apex 20. Slightly forward of this apex, the die plate 15 is slotted inwardly from opposite edges to form the alined slots 21 which nearly meet centrally at the upper face of the die plate, being spaced apart at their inner ends by a narrow neck 22. Forwardly of these slots is a table extension 23. This table extension 23 lies beneath the marginal wall portion 24 of a punching die 25 which has a vertical opening 26 therethrough. This opening 26 is of the shape and size desired for the base member of the corner mount and is provided with two rear side faces 27 arranged at right angles to each other and with their apex 28 in line with the narrow neck portion 22 of the die plate 15. Against these edges 27, the forward folded extremity 30 of the strip 10 is adapted to contact, while a base element is being punched from the base strip and presented to the folded corners of the cap element, as will later appear.

Overlying the depression 17' of the die plate is a resilient plate 35 shaped to engage within this depression with sufficient clearance for the material of the cap strip to extend upwardly between its forward edges and the edges 19 of the recess, and at suitable times this resilient plate 35 is pressed into this depression so that the forward corners of the cap strip just back of the slots 21 are bent upwardly. These forward corners are defined by a pair of cuts 45 (see Figure 11) extending inwardly from opposite sides of the cap strip which almost come together centrally, and these cuts are formed by a pair of rotary cutting knives 40 which are carried by rotary shafts 41 at either side of the line of motion of the cap strip and which are arranged to pass through the slots 21 as the shafts 41 are rotated in opposite directions.

When the strip has been so cut, the spring plate 35 is depressed within the recess 17 which folds up the corners of the strip 10 along the dotted lines shown in Figure 11 at either side of the central uncut zone 46. With the forward corners in this upstanding position they are wiped down over the spring plate 35 as by a pair of wipers 49 which are moved inwardly from opposite sides, successive positions of these wipers being shown in Figures 5 and 7, the folding being about to start in Figure 5 and completed in Figure 7. After the wipers have been retracted, the spring plate 35 is allowed to rise, lifting the strip 10 from behind the edge portions 19 and thus freeing the strip for the next feeding motion.

The second forward portion of the strip 10 which has its corners thus folded is at this time positioned against the walls 27 of the punching die in the position shown in Figure 6. This punching die has a seat 50 at its upper end overlaid by a cover plate 51 and through which is fed a base strip 52. This strip 52 is fed along the seat 50 intermittently between the punching actions of the punch 53. The feeding means may, for example, be a pair of intermittently actuated feed rolls 56 and 57 between which is fed a belt 58 which passes beneath strips 52 and 10 and beneath the punch and die 24 and 53. This belt may be an endless belt, being returned beneath the machine as is illustrated in the Riley Patent No. 1,627,667, the base strip, after the base elements have been punched therefrom, being passed with it between the rolls 56 and 57. The perforated base strip, together with the belt 58, passes between the feed rolls 56 and 57, after which the per-

forated base strip is separated from the belt and is led to a suitable reel (not shown) where it may be rolled up as shown in the Riley patent to which reference has been made. The belt feeds out the completed mounts.

The base strip is coated with adhesive on both faces, but its lower face which is turned toward the cap strip, and portions of which are applied to the caps, is coated with such adhesive for only approximately one-half its width, this being the portion from its rear edge 60 forwardly to form a zone 61, the forward edge of which substantially registers with the widest portion of the punch opening 26 at the rearward extremity of the inclined sides 27. This zone 61 is activated as by any suitable moistening device so that when it passes across the die opening, the activated portion is above the folded-in corner portions of the cap strip therebeneath. The die 53 is relieved from approximate alinement with the rear ends of the walls 27 rearwardly as at 65 so that the rear portion of the base element at 66 which extends beyond the end folded-in corners of the cap is not presented to the folded-in corners of the cap strip rearwardly of the forward end of the strip. For example, as shown in Figure 11, the turned-in corners 61a are not contacted by the portion 66 of the base strip, while the forward turned-in corners 67 are contacted by the activated forward portion of the base strip. The activated adhesive portion of the base element is therefore the only part of the base punching which is presented to the folded-in corners of the cap at the forward end of the cap strip.

As the punch 53 punches the base element from the strip 52 and presents it against the turned-in corners 67 at the forward end of the cap strip, this forward portion of the cap strip is depressed against a resiliently supported anvil 70 beneath it, and the forward cap element is torn away from the next one back of it at the narrow neck 30a. After the punch 53 has been lifted, the cap strip may then be fed forwardly by the next successive step to present the forward folded extremities against the edges 27 of the punching die, and the completed mount is fed out from the punching die on the belt 58. The next uncut section of the cap strip is now in position for the rotary cutters 40 to form the next succeeding set of inward cuts from its edges preparatory to folding the corners of the cap strip back from these edges as previously described.

All these mechanisms are driven in suitable timed relation, the shafts 41 which carry the cutters 40, being connected by miter gears 90 and 91 with a cam shaft 92, which is connected through spiral gearing at 93 with a shaft 94. This shaft 94 is connected through spiral gearing at 95 with a cam shaft 96 having a pair of cams 97 thereon, which, through crank arms 98, actuate slides 99 having the folding elements 49. The resilient finger 35 is actuated to lift up the corner portions 61 of the cap strip preparatory to folding action by a finger 100 which is fulcrumed at 101 and has its rear end turned downwardly as at 102 to engage the plate 35, the other end portion of the lever 100 having a cam follower 103 actuated by a cam 104 carried by the cam shaft 96. The feed roll 11 is also carried by the cam shaft 96 and cooperates with an idler feed roll 110 to feed the cap strip 10. The punch 53 is carried by the platen 112, being guided for vertical motion on the posts 113 and 114, the posts 114 also serving to fulcrum

the folder-actuating arms 98. Springs 115 surrounding the posts 113 and 114 serve to raise the platen and the die, which may be depressed by any suitable means in time with the operation of the rest of the machine, as shown, for example, in the Riley patent to which reference has been made.

The adhesive coating on the upper face of the base strip is not activated during the making of the mount, this being reserved for activation when it is desired to attach the corner mount to a supporting surface such as the page of an album, or the like.

From the foregoing description of the corner mount and the method and machine by which it may be made, it should be evident to those skilled in the art that various changes and modifications might be made without departing from the spirit or scope of this invention.

I claim:

1. The method of making a corner mount, which comprises folding inwardly the forward corners of a strip of material, partly severing said strip from its side edges inwardly and spaced back from said corners and folding in the corners formed by and at the rear of such partial severing, and adhesively securing to said corners first folded in a base piece of sheet material and completing the severance of said strip in substantial alinement with said partial severance.

2. A machine of the class described, comprising means for supporting a strip, means for periodically cutting said strip inwardly from its edges nearly to its center in alined relation while leaving a central zone uncut, means for folding inwardly the corners of said strip back of each cutting, means for feeding said strip forwardly step by step by substantially the width of said folded-in portions, a punching die in alinement with which said folded-in corners will register after a subsequent feeding step before which said cutting and folding means have again operated, means for intermittently feeding a base strip up side down and having an activated adhesive coating on a portion of its lower face, a punch for said die, and means for periodically actuating said punch in said die to punch a base element from said base strip and present its activated face against the corners of said cap strip in alinement therewith and to complete the severance of the cap to which said base element is so secured from the remainder of said cap strip at said central portion.

3. A machine of the class described, comprising a strip supporting plate having a recess of a width to receive a cap strip and having a pointed forward wall formed by two rectangularly related edge faces, said plate having a pair of oppositely disposed slightly spaced slots forwardly of and adjacent to the point of said wall, a knife mounted for motion through each slot to cut a cap strip supported on said plate inwardly from opposite sides leaving a narrow central uncut portion, means for actuating said knives, means for forcing said strip into said recess to lift the forward corners of said strip back from the line of

said cuts, means for wiping said corners inwardly, means for intermittently feeding said strip forwardly by substantially the width of said folded corners, a die forwardly of said plate and having wall openings opposed to and against which the front folded edge of said strip may engage, means for feeding a base strip having an activated adhesive on its lower face across the top face of said die, and a punch movable through said die for punching a base piece from said base strip and presenting its adhesively coated face against the folded corners of said cap strip and effective to complete the severance of the forward folded portion to which said base piece was so presented from the remainder of said cap strip.

4. A machine of the class described, comprising a strip supporting plate having a recess of a width to receive a cap strip and having a pointed forward wall formed by two rectangularly related edge faces, said plate having a pair of oppositely disposed slightly spaced slots forwardly of and adjacent to the point of said wall, a knife mounted for rotation about an axis to pass through each slot to cut a cap strip supported on said plate inwardly from opposite sides leaving a narrow central uncut portion, means for rotating said knives, means for forcing said strip into said recess to lift the forward corners of said strip back from the line of said cuts, means for wiping said corners inwardly, means for intermittently feeding said strip forwardly by substantially the width of said folded corners, a die forwardly of said plate and having wall openings opposed to and against which the front folded edge of said cap strip may engage, means for feeding a base strip having an activated adhesive on its lower face across the top face of said die, and a punch movable through said die for punching a base piece from said base strip and presenting its adhesively coated face against the folded corners of said cap strip and effective to complete the severance of the folded forward portion of said cap to which said base piece was so presented from the remainder of said cap strip, said punch having its lower face relieved over a portion of its area to thereby avoid pressing a portion of said base piece back of the folded corners of said cap strip against said cap strip.
